UNITED STATES PATENT OFFICE.

FRANK K. ATKINS, OF NEW YORK, N. Y., AND EARL F. ATKINS, OF ARLINGTON, NEW JERSEY.

FILTER.

1,273,127.

Specification of Letters Patent. Patented July 23, 1918.

Application filed September 18, 1917. Serial No. 191,928.

To all whom it may concern:

Be it known that we, FRANK K. ATKINS, a citizen of the United States, and a resident of the city, county, and State of New York, and EARL F. ATKINS, a citizen of the United States, and a resident of Arlington, county of Hudson, State of New Jersey, have invented certain new and useful Improvements in Filters, of which the following is a specification.

Our present invention relates to devices for filtering fluids in which the solids filtered therefrom are built up on the filtering surfaces.

One of the objects of our invention is to provide simple and efficient means by which the solids may be readily removed from the filter.

Another object of the invention is to provide a filter which will enable the filtering processes and the washing and removal of the solids to be conducted in a most efficient manner.

With these and other objects in view our invention consists of certain novel features of construction, combination and arrangement of parts as will be more fully described and pointed out in the appended claims.

In the drawings, Figure 1 represents a plan view of an illustrative form of our invention;

Fig. 2 is an elevation, partly in section, of the form illustrated in Fig. 1;

Fig. 3 is an end elevation looking from the left of Fig. 1;

Fig. 4 is an enlargement of a section on line 4—4 of Fig. 1;

Fig. 5 is a view similar to a portion of Fig. 3 but with the parts in different positions;

Fig. 6 is a side elevation of our preferred form of cutter; and

Fig. 7 is a partial sectional end elevation of Fig. 2.

Fig. 8 is a view similar to Fig. 2 with the parts in a different position.

The corresponding parts are referred to both in the drawings and in the specification by similar reference characters.

At the top of the supporting legs 10—10 are a pair of trunnions 11—11 to which trunnions are fastened the side bars 12—12.

Fastened to these side bars is a fixed head 13, as shown at the left of Figs. 1 and 2 and at the opposite ends is fastened an abutment member or screw standard 14. Slidingly mounted on the bars 12—12, between the head 13 and the screw standard 14, is a movable or follower head 15, and, in our preferred form, between the follower head 15 and the fixed head 13 is provided a series of filter plates 16 and filter frames 17. These filter plates and frames, in general, are of the usual construction, and are arranged so that filter cloths may be placed on either side of each filter plate and are furthermore provided with eyes 18, 19, 20, the openings in the eyes 18 communicating with alternate plates 16 of the series, the openings in eyes 19 with the remaining plates and the openings in eyes 20 with the interior of the frames 17. Each of these eyes is in alignment so that the openings therein, when the series of plates and frames are placed in position, form conduits from one end of the series to the other. The plates are furthermore provided with fluid outlets 21 for which in the form illustrated, stop cocks 22 are supplied. The plates 16 are each provided with an opening 41 forming an inactive area of the plate. The purpose of this opening will be hereinafter described.

The follower head 15 has a rotatable member 23 journaled therein, the member 23 having a central aperture 24 for a purpose to be described hereafter. The member 23 is provided with a liquid-tight stuffing box. The aperture 24 is normally closed by a gate 25 hinged on one of the rods 61 and against this gate bears a screw 26 having a capstan nut 27. The other end of the screw enters the plate 70 hinged to one of the rods 61 and the nut 27 also bears against plate 70. The whole arrangement provides a means by which, when the capstan nut 27 is turned with the parts in the position shown in Fig. 2, the filter plates and frames, with the filter cloths between them, will be clamped together to make the joints between them liquid-tight.

A fixed inlet pipe 28 is provided with its axis in the axis of the trunnions 11—11. By a liquid-tight swivel, the pipe 28 is connected through piping 29 to an inlet pipe

30, through which the liquid to be filtered will enter the filter through a suitable opening in the head 13 communicating with the conduit formed by the eyes 20 of the plates 5 and frames, this conduit opening through the frames 17 to the interior of the filter. Also connected to the pipe 29 and controlled by suitable valves are pipes 31, 32, which also communicate, through suitable openings in 10 the head 13, with the conduits formed by the eyes 18 and 19 respectively. A pipe 33 also communicates through suitable valves with the pipe 29 and with the interior of the filter through the opening 34. A pipe 15 35, valve controlled, connects with pipe 30, so that the filter may be drained when desired.

With the apparatus as described thus far, in the position shown in Fig. 2, the filtering 20 process is carried on much as in the usual way. The liquid to be filtered, usually under pressure, is passed through the pipe 30 into each of the frames 17 and the main body of the filter and the filtrate passes through the 25 filter cloths and into the conduits on the faces of the filter plates into the outlets 21, and through the cocks 22 into any appropriate trough. When the deposit on the plates has become sufficiently thick, the pressure 30 is cut off and the solids may then be washed in the usual manner. For instance, it may be done by passing the washing solution through pipe 30, into and through the solids and out of the cocks 22. With this 35 flow going on, the cocks 22 of plate 16 which communicate with the openings in eyes 18 may be closed and washing solution forced through eyes 18. This causes a reverse flow through the solids from one plate to the opposite plate. This circulation may be reversed by similarly passing the solution through eyes 19 when the cocks 22 of the plates 16 communicating with eyes 19 are closed. Compressed air may be passed 40 through the pipe 33 to completely dry the cakes of solids built up on the filter plates 45 and also to aid in draining the press.

Our invention further contemplates a convenient means for removing these solids 50 without the necessity of opening the filter or disturbing the filter cloths. To this end preferably we provide a series of cutters 36, on a shaft 37. This shaft 37 is mounted eccentric to the filter plates, one end of 55 the shaft having a bearing 64 fastened in the opening 24 of the rotatable member 23 in the follower head 15, and an extension 38 on the shaft 37 has a bearing in a rotatable member 39 in the fixed head 13. This extension 38 is connected to the shaft 37 by a bolt 62 which holds the two parts together, and a clutch 40 is provided so that the two parts rotate as one shaft. The member 39 has a liquid tight stuffing box in the head 13.

60 As shown best in Fig. 4, the cutters 36

are designed so that, when the filtering process is going on, they occupy the full line position of Fig. 4, and are then in alignment with the openings 41 in the filter plates 16, these openings 41 being in alignment. The cutters are, therefore, located so that, as the solids are built up on the active faces of the filter plate between the openings 41 and the exterior edges of the plates, the cutters do not interfere with the 70 filtering operation nor do they become embedded in the solids. It will be understood that the filter cloths have openings in their centers corresponding to the openings 41, as well as with the openings through the 80 eyes 18, 19 and 20.

If the filter plates and the cutters are rotated relatively while at the same time the shaft 37 is slowly rotated, the cutting edge 42 of the cutter will cut out the inside of 85 the cake formed on the filter plate and break it up. This rotation and feed of the cutter may be provided in any suitable way, and as a preferred form of such mechanism, we have shown a shaft 43 mounted in suitable 90 bearings connected to the head 13 and follower head 15 and receiving its power through a gear 44. To the rotatable member 23 is attached a gear 45, meshing with gear 44, and to the rotatable member 39 is 95 attached a gear 46, meshing with a gear 47 attached to the shaft 43. Gears 44 and 47 are of the same size, as are gears 45 and 46. The rotation of the shaft 43 therefore rotates the members 39 and 23 at the same speed 100 and thus carries the shaft 37 bodily around inside of the openings 41, thus producing a relative rotation between the cutters 36 and the filter plates. Loosely mounted on a hub on the member 39 is a gear 48 meshing with a gear 49 also attached to the shaft 43. The gears 46-47 and 48-49 are so proportioned that, in the form which we have illustrated, the gear 48 will rotate faster than the gear 46. On the face of the 110 gear 48 is a lug 50, of which more than one may be provided, if desired. Fastened to the end of the extension 38 is a lever 51 having on its inner side a lug 52, which, when the lever 51 is in the position shown in Fig. 115 3, is arranged to be contacted by the lug 50. Preferably we provide a roller 63 arranged to form the top of the lug 52. As the shaft 43 rotates, therefore, the cutter shaft 37 is carried around bodily by reason of its bearings in the rotatable members 23 and 39 and at the same time, by reason of the differential motion between the bodily rotation of the cutters and the rotation of the gear carrying the lug 50, the lever 51 is turned 120 clockwise slightly for each complete rotation of the cutters. This has the effect of carrying the cutter edge 42 from the position shown in full lines in Fig. 4 to the dotted line position shown in that figure, the lever 125 130

51 ultimately reaching the position shown in Fig. 5, at which time, because of the eccentric mounting of the shaft 37, the lug 50 will pass over the top of the lug 52, 5 and there will, therefore, be no further rotation of the shaft 37 on its own axis. The roller 62, forming the top of lug 52, prevents undue wear when the parts are in the position of Fig. 5. This separation of these 10 two lugs acts as an automatic cut-out to stop the feed of the cutter when its edge has reached the outer edge of the active surface of the filter plates. If desired, the rotation of the heads 23, 39 may be continued 15 without any danger of injuring the cutters by contact with the edges of the plates or frames. We have provided a locating stop 54 by which the operator can readily set the cutters to their correct inner position by 20 contact of the adjustable screw head 55 therewith, and an adjustable stop 56 may also be provided for contact with the lever 51 when the cutters are in their outer position, as shown in Fig. 5.

25 On the rear of the frame 10 is mounted in suitable bearings a vertical shaft 57 having a pinion 58 attached thereto and driven by suitable gearing 59 and a pulley 60.

The shaft 37 is provided with the extension 38 and the loose bearing 64 so that it with its cutters may be removed from the filter. It is obvious that if the bolt 62 and bearing 64 are removed, the shaft 37 with its cutters may be then readily removed through 35 the right-hand end of the press.

After the filtering operation is completed and the solids have been washed and dried as desired, the filter is swung on the trunnions 11 in the direction of the arrow, Fig. 40 2, until the plates and frames are horizontal as shown in Fig. 8. When the filter stands in this position, the gear 44 meshes with the gear 58 so that as the pulley 60 is rotated, the shaft 43 will be rotated to operate the 45 cutters and the gears 45 and 46 will be turned to carry the shaft 37 bodily around the interior of the plates. Before the filter is brought to this vertical position, the screw 26 is released so that the outlet gate 25 and 50 plate 70 may be swung to one side to open the outlet 24. The pulley 60 is started and the cutters rotate to break up the solids and carry them to the openings 41 through which they drop to the opening 24 through which 55 they pass out of the filter through opening 71 in the screw standard 14.

The capstan screw 26 is used not only to hold the gate 25 in place, but also to hold the plates and frames together, and if no other 60 device were provided, it would be obvious that, when the nut 27 is operated to release the gate 25, the plates and frames would also fall apart. To prevent this, we provide a pair of screws 61 which are threaded 65 into the screw standard 14 and rest against

the follower 15. These screws 61 are tightened up after the plates and frames are clamped in place by the screw 26 so that thereafter the screw 26 may be released without releasing the plates and frames.

70

In our preferred form the cutter blades 36 are arranged not only to break up the cake, but are also arranged so that the solids are forced by the blade into the openings 41, which arrangement permits the removal of 75 the solids without any effort on the part of the operator. Furthermore, we have found it desirable to arrange the blade so that the cutting edge 42 will have approximately the same cutting angle in relation to the solids 80 as it is fed outward and particularly that this cutting angle shall be very flat or acute. Furthermore, while it is desirable that the width of the cutter 36 shall be great enough to remove substantially all of the solids by 85 running very close to the filter cloths, we have found that such a width, if continued to the support for the blade on the shaft 37, tends to clog the filter, especially when the cutter is removing the last of the solids, the swinging 90 of the blade across the plate bringing its supporting shank close to the edge of the opening 41.

The design shown in Figs. 4 and 6 accomplishes these ends. In this form, the cutter 95 36 is fastened to a thin steel shank 65, which is fastened to shaft 37. The front edge of the shank is preferably made into a cutting edge, as at 66. The shanks are spaced on shaft 37 by the distance pieces 67.

100

With some materials, the cakes build up so loosely that filtration may be carried on after solid cakes are formed between the plates, in which event, solids will form in the openings 41, thus "freezing" the cutters. 105 To prevent this we provide preferably a thin metal tube 68 which we place in the openings 41 as shown in Figs. 2 and 4. This tube is passed through the openings 71 and 24 and preferably, for ease in placing and removing it, is not a complete tube, but has an opening longitudinally, as shown in Fig. 4, and is also tapered longitudinally. When the tube is used, it is inserted before the filtering operation begins. Its presence prevents the solids building up in the openings 41 around the cutters. If any solids do so build up through the space between the edges of the longitudinal opening in the tube, they will be around the shaft 37 only 110 and will not prevent its operation. After the cakes are built, the tube is withdrawn and the cutters thrown into operation, as previously described.

115

By the construction described, we obtain 125 all of the advantages of filtration with the well-known plate and frame filter press, in which the plates are held in vertical position while the cakes are being built up and while they are being washed and treated. It has 130

been found by experience that in this type of press the cakes are built up uniformly between two opposite filter plates, whereas in the forms of presses where the filter plates are horizontal, there is a tendency to build up the solids on the top side of each plate at a faster rate than on the lower side, thus reaching a thickness of cake on one side which will stop any further filtration before 10 the cake on the opposite plate has been built up to the same degree.

By mounting such a press on the trunnions 11-11 we have also provided a means by which the press can be turned to a position wherein the material can be removed by 15 gravity from the press without opening the plates and frames. We, therefore, have combined in our novel filter press the advantages of the usual plate and frame press, in 20 which the filtering plates are vertical, with an arrangement by which the solids can be mechanically removed without opening the press.

It will also be understood that the cutters 25 which we have illustrated may be used to cleanse the filter cloths while they are in place by passing a fluid reversely through the cloths to raise them into contact with the blades 36 while the latter are rotating in 30 their outer position.

It has also been found that, in certain cases, a better washing effect for the plates would be obtained if the washing water is being passed through the cakes while the 35 plates are in horizontal position. This is particularly true of materials which are liable to break up and fall while being washed. If this should occur while the plates are in vertical position, an opening or 40 bare spot on the filter cloth is thereby made, through which the wash water will find a ready passage without going through the remainder of the cake. When the plates are horizontal this tendency to fall is obviated. 45 With our novel arrangement we are therefore able to carry on the filtering process with the plates in the vertical position and then to carry on the washing process with them in their horizontal position.

50 The embodiment of our invention may be varied widely. While in our preferred form we rotate the cutter, we are not limited to this particular arrangement, since other structures in which the plates rotate while 55 the cutter is swung in between the rotating plates will have the same effect.

While preferably we have adapted our novel means for breaking up and removing the solids to a press of the plate and frame 60 type, it will be understood that such mechanism may be applied to any other type of filter. It will also be understood that the swinging of the filter from the horizontal to the vertical position is not essential, since the 65 press would operate if the filtering operation

were carried on while in a vertical position, the cutters at such time being at rest.

While we have shown a central aperture in the plates, such arrangement is by no means essential, it being possible to locate the aperture and cutters in other positions in relation to the plate. 70

We claim:—

1. In a filter, a filter plate having a non-filtering area within its periphery, means for 75 building up a cake on said plate, a cutter normally located opposite said non-filtering area while the cake is building and means to move said cutter and said plate relatively to break up and remove the cake. 80

2. In a filter, a pair of filter plates spaced apart, each plate having a central opening and such openings being in alinement, a cutter normally located in the space between the plates and in alinement with said openings, 85 means to deposit solids on said plates and means to move said plates and said cutter relatively to break up and remove such deposits.

3. In a filter, a pair of filter plates spaced apart, each plate having a central opening and such openings being in alinement, a cutter normally located in the space between the plates and in alinement with said openings and means to move said cutter through the 95 space between said plates and across the active faces thereof.

4. In a filter, a pair of filter plates spaced apart, each plate having a central opening and such openings being in alinement, a cutter normally located in the space between the plates and in alinement with said openings, means to deposit solids on said plates and means to feed the cutting edge of said cutter through such deposits to break up and remove them. 100 105

5. In a filter, a series of filter plates spaced apart, each plate having a central opening and such openings being in alinement, a 110 shaft extending through said openings, a series of cutters on said shaft, each normally positioned in a space between a pair of said plates and in alinement with said openings and means to rotate said shaft to move said cutters across the active faces of said plates. 115

6. In a filter, a series of filter plates spaced apart, each plate having a central opening and such openings being in alinement, a shaft extending through said openings and eccentrically located in relation to said 120 plates, a series of cutters on said shaft, each normally positioned in a space between a pair of said plates and in alinement with said openings and means to rotate said shaft to move said cutters across the active faces of 125 said plates.

7. In a filter, a series of filter plates spaced apart, each plate having a central opening and such openings being in alinement, a shaft extending through said openings and 130

eccentrically located in relation to said plates, a series of cutters on said shaft, each normally positioned in a space between a pair of said plates and in alinement with 5 said openings, means to rotate said plates and said cutters relatively to each other and means to rotate said shaft to move said cutters across the active faces of said plates.

8. In a filter, a series of filter plates spaced 10 apart, each plate having a central opening and such openings being in alinement, a shaft extending through said openings and eccentrically located in relation to said plates, a series of cutters on said shaft, each 15 normally positioned in a space between a pair of said plates and in alinement with said openings, means to rotate said plates and said cutters relatively to each other and means to rotate said shaft to move said cutters across the active faces of said plates, said last named means being constructed and arranged to stop the rotation of said shaft automatically when said cutters reach the outer edges of said plates.

20 25 9. In a filter, a pair of heads, a series of filter plates and frames held therebetween, each of said plates having a central opening and such openings being in alinement, a rotatable member in each of said heads, a shaft eccentrically and rotatably mounted 30 in said members, a series of cutters on said shaft, each cutter being located in one of the frames and normally in alinement with said openings, means to rotate said members and means to rotate said shaft as said 35 members are rotating.

40 45 10. In a filter, a pair of heads, a series of filter plates and frames held therebetween, each of said plates having a central opening and such openings being in alinement, a rotatable member in each of said heads, one of said heads having an outlet therethrough in alinement with the openings in said plates, means to close said outlet, a shaft eccentrically and rotatably 50 mounted in said members, a series of cutters on said shaft, each cutter being located in one of the frames and normally in alinement with said openings, means to rotate said members and means to rotate said shaft as said members are rotating.

55 60 11. In a filter, a fixed head, a movable head having an outlet therethrough, an abutment, a series of filter plates and frames between said heads, each plate having a central opening and said openings being in alinement with each other and with said outlet, means to close said outlet, clamping means between said movable head and said abutment to clamp said plates and frames between said heads and to operate said outlet-closing means, and means to hold said plates and frames in clamped position while said clamping means is operated to permit said outlet to be opened.

12. In a filter, a fixed head, a movable head having an outlet therethrough, an abutment, a series of filter plates and frames between said heads, each plate having a central opening and said openings being in 70 alinement with each other and with said outlet, means to close said outlet, clamping means between said movable head and said abutment to clamp said plates and frames between said heads and a support for said 75 heads and abutment constructed and arranged to permit said plates to be swung from vertical position to horizontal position and back again.

80 85 13. In a filter, a fixed head, a movable head having an outlet therethrough, an abutment, a series of filter plates and frames between said heads, each plate having a central opening and said openings being in alinement with each other and with said outlet, means to close said outlet, clamping means between said movable head and said abutment to clamp said plates and frames between said heads, a support for said heads 90 and abutment constructed and arranged to permit said plates to be swung from vertical position to horizontal position and back again, cutters, and means to cause said cutters to break up the solids formed on said plates and remove them through said openings and said outlet when said plates are in horizontal position.

95 100 14. A filter having a series of filter plates, means for supporting said filter constructed and arranged to permit it to be swung so that said plates are either horizontal or vertical, means for supplying solution to said filter to build up solids on said plates when said plates are vertical and means to break up and remove such solids from between said plates when said plates are horizontal.

105 110 15. In a filter, a horizontal filter plate having a central opening, means for building up a cake thereon, a cutter blade normally located above said plate and in alinement with said opening, said blade being mounted to permit its cutting edge to be swung from a position adjacent the edge of said opening to a position adjacent the outer edge of said plate, and means to rotate said plate and said blade relatively as the cutting edge is being swung from its inner to its outer position.

115 120 16. In a filter, a horizontal filter plate having a central opening, means for building up a cake thereon, a cutter blade normally located above said plate and in alinement with said opening, said blade being mounted to permit its cutting edge to be 125 swung from a position adjacent the edge of said opening to a position adjacent the outer edge of said plate and means to rotate said plate and said blade relatively as the cutting edge is being swung from its inner to its 130

outer position, said blade being shaped so as to force the solids broken up by the cutting edge toward and into said opening.

17. In a filter, a horizontal filter plate having a central opening, means for building up a cake thereon, a cutter blade normally located above said plate and in alignment with said opening, said blade being mounted to permit its cutting edge to be 10 swung from a position adjacent the edge of said opening to a position adjacent the outer edge of said plate and means to rotate said plate and said blade relatively as the cutting edge is being swung from its inner to its 15 outer position, said blade being shaped so as to force the solids broken up by the cutting edge toward and into said opening and to permit the solids to discharge into said opening.

18. In a filter, a pair of horizontal filter plates spaced apart and having aligned central openings therein, means for depositing solids on said plates, a cutter blade located between said plates and pivotally mounted 25 eccentrically of said plates to permit its cutting edge to be swung from a position adjacent the edge of said opening to a position adjacent the outer edge of said plates, and means to rotate said plates and said blade 30 relatively as the cutting edge is being swung from its inner to its outer position, the cutting edge of said blade being only slightly narrower than the space between said plates and said blade being relatively thin between 35 the cutting edge and the blade support.

19. In a filter, a pair of horizontal filter plates spaced apart and having aligned central openings therein, means for depositing solids on said plates, a cutter blade located 40 between said plates and pivotally mounted eccentrically of said plates to permit its cutting edge to be swung from a position adjacent the edge of said opening to a position adjacent the outer edge of said plates, and 45 means to rotate said plates and said blade

relatively as the cutting edge is being swung from its inner to its outer position, said blade being shaped and mounted so that its cutting edge maintains a substantially constant acute cutting angle in relation to the solids 50 on said plates as said blade is swung from its inner to its outer position.

20. A filter having a series of alternate filter plates and filter frames, filter cloths between said plates and frames, means for clamping said plates and frames together to make the joints therebetween liquid-tight, said plates and cloths being provided with openings, means for supplying the solution to be filtered to said press, means whereby 60 the remaining unfiltered solution may be drained from the filter after the solids have been deposited, and mechanism operative while said plates and frames are clamped together, for breaking up and removing the 65 solids from the filter through said openings after the filter is drained.

21. In a filter, a pair of filter plates spaced apart, each plate having a central opening and such openings being in alignment, a cutter normally located in the space between the plates and in alignment with said openings, means to deposit solids on said plates, means to prevent solids depositing around 70 said cutter, and means to feed the cutting edge of said cutter through such deposits to 75 break up and remove them.

22. In a filter, a series of filter plates spaced apart, each plate having a central opening and such openings being in alignment, means to deposit solids on said plates, cutters between said plates and normally in alignment with said openings, removable means to prevent solids depositing around 80 said cutters when in normal position and 85 means to move said cutters to break up and remove the solids.
